UNITED STATES PATENT OFFICE

DOMINICK PECCERILLO, OF NEW HAVEN, CONNECTICUT

GAME

Application filed December 17, 1930. Serial No. 502,965.

This invention relates to an improvement in games and of the type commonly known as "skee-ball," that is, a field divided into sections with means for ejecting a ball onto the field, the score depending upon the portion of the field in which the ball first lands.

The object of this invention is to provide a simple toy, the operation of which may be controlled by a coin-mechanism and which provides for the return of the balls to a series of pockets indicating the counts, and the invention consists in the construction as hereinafter described and particularly recited in the claims.

15 In the accompanying drawings:

Fig. 1 is a plan view of a game constructed in accordance with my invention;

Fig. 2 is a sectional view on the line 2—2 of Fig. 1;

20 Fig. 3 is a sectional view on the line 3—3 of Fig. 1;

Fig. 4 is a sectional view on the line 4—4 of Fig. 1 enlarged; and

25 Fig. 5 is a sectional view on the line 5—5 of Fig. 1 enlarged.

In carrying out my invention, I employ an inclined board 10 suitably supported by a frame 11 and on the board are a series of eccentrically-arranged oval fields 12, 13, 14, 30 15 and 16 formed by fences 17, 18, 19, 20, 21 and 22. At the lower point of each field is a hole 23 leading to a cage 24 having a number of pockets 25 corresponding to the holes in the field. The lower ends of these pockets 35 are normally closed by a gate 26 mounted on a rock-shaft 27 and held in the closed position by springs 28.

To one end of this shaft a clutch-member 29 is fixed and mounted in the casing in line with the shaft is a stub-shaft 30 having an operating button 31, and to this stub-shaft is fixed a clutch-member 32 complementary to the clutch-member 29, the adjacent faces of the two members being provided with recesses 33 and 34 to form a pocket for a coin entered through a coin-slot 35, this coin coupling the two clutch-members so that turning the button 31 will turn the shaft 27.

50 Below the cage 24 is a chute 36 under which balls will fall from the cage when the gate is

open and from which they roll into line with a gun-barrel 37, the inner end of which is bowed upward, and in this barrel is a plunger 38 pressed forward by a spring 39 and retracted by a handle 40.

A predetermined number of balls will be placed in the cage and the player, dropping a coin in the slot 35, can then turn the button 31 and release the balls which fall out through the chute 36 and roll toward the gun 37 which they can enter one at a time. After a ball has entered the gun, the handle 30 is withdrawn and released, which shoots the ball toward the field, the object being to enter the smaller field. If it does not enter this field, it enters one of the others and from that field returns to one of the pockets in the cage 24, and this operation is repeated until all the balls are exhausted. A glance at the cage will indicate on which field the ball has landed and the count is made accordingly. The device is then ready for another operation.

This produces an attractive amusement device, simple in construction and not liable to be deranged.

I claim:

1. A game comprising a plurality of fields formed by eccentric fences, openings in each field, a cage having a series of pockets corresponding in number to the number of fields, tubes extending from said openings to said pockets, a coin-controlled gate closing the said pockets, a chute below said cage, and a spring-gun to which the balls are delivered from said chute.

2. A game comprising a plurality of fields formed by eccentric fences, openings in each field, a cage having a series of pockets corresponding in number to the number of fields, tubes extending from said openings to said pockets, a coin-controlled gate closing the said pockets, a chute below said cage, and a spring-gun having an upwardly-bowed inner end to which the balls are delivered from said chute.

3. A game comprising a series of fields formed by a series of oval fences eccentrically arranged, a hole in the lower portion of each field, a cage below said field and provided with a series of pockets corresponding in num-

ber to the series of fields, tubes extending from said holes into said pockets, a gate closing the lower end of said pockets, a rock-shaft on which the gate is mounted, coin-controlled means for moving said gate, a chute below said gate, a gun-barrel into the side of which the chute opens, a spring-plunger mounted in said barrel, and means for placing said spring-plunger under pressure whereby when the pressure is removed, a ball will be ejected from the gun toward the fields.

5 In testimony whereof, I have signed this specification.

DOMINICK PECCERILLO.
